(57) **CLAIM**

The ornamental design for a device tag for display of electrical devices, as shown and described.

DESCRIPTION

(62) Division of application No. 29/097,815, filed on Dec. 15, 1998, now Pat. No. Des. 416,050.

FIG. 1 is a front elevation of the tag showing our new design;

(51) **LOC (7) Cl. 19-08**

FIG. 3 is a rear elevation of the tag of FIG. 1;

(52) **U.S. Cl. D20/22; D20/23; D13/154**

FIG. 3 is a side elevation of the tag of FIG. 1; and,
FIG. 4 is a perspective view showing the tag of FIG. 1 in
cooperative orientation with respect to an electrical display
device.

(58) **Field of Search** D20/10, 11, 22-28,
D20/40; 40/1.5, 299.01, 300.316, 27.5;
283/81; D13/154, 157

The broken lines are shown for illustrative purposes only
and form no part of the claimed design.
